STOP MOTION FOR ROVING AND SPINNING MACHINES

Walter J. Scott, Woonsocket, R. I.

Application April 28, 1931. Serial No. 534,503

7 Claims. (Cl. 19—165)

My present invention relates to stop motions for textile machines, and has particular references to stop motion for roving and spinning machines.

5 The stop motions heretofore used in drawing machines have utilized imperfections in the sliver, such as enlargements, or the weight of a broken sliver, to shift the stop control parts and stop the machine. Such positive actuation of the stop motions by the sliver itself is not possible in the roving and spinning machines, where the threads lack the necessary weight to positively shift the stop control parts.

15 The finer threads, however, have much greater tensile strength than the larger sliver, and may be utilized indirectly by utilizing gravity to shift the stop control parts and holding these parts against movement by the tensile strength of the threads. One object of my invention is to so proportion and mount a stop motion as to normally hold the control parts against movement under the influence of gravity by the tensile strength of the threads.

25 Another feature of stop motions as applied to drawing operations has resided in the application of the stop motion to the machine as a whole. While this feature is desirable for all the heavier drawing operations, it is not desirable for the finer roving and spinning frames, where the number of spindles is large. Moreover, it often happens that replenishment of a particular thread upon breakage, is more advantageously deferred until a general replenishment 35 is necessary. In such case, it is preferred to permit further operation of the remaining spindles, this arrangement also permitting use of part of the roving or spinning frame when desired. Another object of my invention is to so 40 mount stop motions on a roving or spinning machine as to permit independent control of individual spindles.

With these and other objects and advantageous features in view, my invention consists 45 of a novel arrangement of parts more fully disclosed in the detailed description following, in conjunction with the accompanying drawing, and more particularly defined in the appended claims.

50 In the drawing:

Fig. 1 is a diagrammatic view, partly in section, showing the mounting of the novel stop motion;

Fig. 2 is a front elevation thereof;

55 Fig. 3 is a view similar to Figure 2, with parts

broken away, the interior parts being in turned position:

Fig. 4 is a section on the line 4—4 of Figure 3; Fig. 5 is a rear elevation of Figure 3; and Fig. 6 is a diagrammatic view showing the machine belt shifting apparatus, and the control therefor.

It has been found desirable to utilize the tensile strength of a fine drawn thread for holding a gravity responsive stop element against contacting to close the stop circuit; and it has also been found desirable to mount a plurality of such stop elements on a roving or spinning machine and to provide independent controls for each element.

I have therefore devised a stop device which includes a pivoted element, swingable under the influence of gravity to close a stop circuit; and I have utilized the strength of the thread to normally hold this swingable element out of contacting position. I have also devised a control for positively holding any desired swingable control out of contacting position; and the following is a detailed description of a specific construction which embodies the principles of my invention.

Referring to the drawing, the reels 10 containing the thread are mounted as usual to feed the thread through the guides 11 to the back feed rolls 12, the thread then passing through the twist holding rolls 13 to the front feed rolls 14, and then through the usual guide opening 15 to the spindle 16. The spindle may be the cap or butterfly type, dependent on the size of the thread, but as illustrated is of the cap type.

The novel stop motion, designated generally as 17, is mounted between the reel and the back feed rolls, and includes a base 18, preferably of cast metal, with bored lugs 19 through which the hinge rod 20 extends, a screw or the like 21 in the center lug serving to lock the hinge rod in place.

Pivottally mounted on the hinge rod between the end and center lugs are two contact rods 100 or tubes 22, the upper ends being threaded to receive the threaded ends of wires 23 which are looped to threadingly receive the threads 11; a lock nut 24 is used to hold each wire in adjusted position.

The base 18, as best shown in Figures 2 and 4, is transversely bored at each end to receive contact bolts 25, which are locked in place by lock nuts 26, insulating washers 27 being positioned between the lock nuts and the base. A

105

110

contact bar 28 is mounted on the projecting ends of the bolts 25, between the heads thereof and lock nuts 29, and is adapted to be contacted by the contact rods as hereinafter described.

A contact control bar 30 extends through the center portion of the base, the rear portion being bent to provide a manually operable handle 31 and the front portion mounting a control blade 32 which is secured between lock nuts 33. The blade 32, as best shown in Figures 2 and 3, has two arms with the corners bent so as to facilitate engagement of the arms with the contact bars 22 on rotation of the control handle 31. Suitable stops 31a are provided on the base for the control handle.

Referring to Figure 6, the electric control circuit includes a line switch 34, an electromagnetic release 35, a spring-held latch member 36, a belt shift rod 37 provided with an adjustable collar 38 against which the latch member presses, and the usual wiring to make the base 18 and the bar 28 parts of a normally open circuit.

25 The operation of the improved stop motion is as follows:

The threads from one, two or more reels are threaded through the eyes of the wires 23, and then passed through the guide 11 to the back feed rolls. The tension of the threads on the eyes normally keeps the contact bars in upright position, as shown in full lines in Figure 1, the setting of the stop motion being such as to gravity-urge the contact rod downwardly, as indicated in dotted lines in Figure 1.

If a thread breaks, the associated contact rod falls, closes the stop circuit, and thus releases the latch member to shift the belt and stop the machine. If the attendant does not 40 wish to repair the break immediately, the handle 31 is turned, thus holding the contact rods positively away from the contact bar, and permitting operation of the remaining spindles. This arrangement also permits use of as many 45 spindles as are desired, up to the full capacity of the machine.

My improved stop motion therefore utilizes the strength of the thread to hold a stop motion contact rod from contacting position, and is adapted to cut out one or more spindles as desired without affecting the operation of the remaining spindles.

While I have described one specific embodiment of my invention, such changes in arrangement and in proportions may be made as are within the spirit and the scope of my invention as defined in the appended claims.

I claim:

60 1. In a stop motion, a base, a contact element thereon, a second contact element hingedly mounted on said base and movable towards said first contact element, means operable by tensile strength of the thread for holding said second contact element away from contacting engagement, and additional means mounted on said base, movable for engaging and positively hold-

ing said second contact element away from contacting engagement.

2. In a stop motion, a base, a contact element thereon, a second contact element hingedly mounted on said base and gravity-urged towards said first contact element, means operable by tensile strength of the thread for holding said second contact element away from contacting engagement, and additional means mounted on said base, movable for engaging and positively holding said second contact element away from contacting engagement. 80

3. In a stop motion, a base, a contact element mounted on said base and spaced therefrom, a second contact element hingedly mounted on said base and movable to engage said first contact element and having a thread receiving portion thereon, and an element mounted on said base and movable to engage said second contact element and lock it against contacting engagement with said first contact element. 85

4. In a stop motion, a base, a contact element mounted on said base and spaced therefrom, a second contact element hingedly mounted on said base and gravity-urged to engage said first contact element and having a thread receiving eye portion thereon, and an element mounted on said base and movable to engage said second contact element and lock it against contacting engagement with said first contact element. 90

5. In a stop motion, a base, a contact bar mounted transversely thereof and spaced therefrom, a plurality of contact rods hingedly mounted on said base and engageable with said contact bar, said rods having eye portions to receive threads, and a control member mounted on said base and movable to engage said contact rods and lock said contact rods against contacting engagement with said contact bar. 95

6. In a stop motion, a base, a contact bar transversely mounted on said base and spaced therefrom, a plurality of contact rods hingedly mounted on said base in a position to be gravity-urged to engage said bar, a thread receiving portion on each of said rods, a movable member having a locking member on the end thereof mounted on said base and movable to engage said rods to lock them against contacting engagement with said bar. 100

7. In a stop motion, a base positioned in generally a vertical plane, a fixed contact element, means for fixedly supporting said element from said base and in spaced relation thereto, a movable contact element located between said fixed element and base, means on said base for pivoting said movable contact element at its lower end and at a point below said fixed central element and at a location to swing by gravity away from said base and towards said fixed element, and a thread eye on the end of said movable contact element thru which a thread extends that the tension on the thread may maintain the movable contact element out of contact with the fixed contact element. 105
